UNITED STATES PATENT OFFICE

2,652,856

FAUCET FOR DISPENSING CARBONATED BEVERAGES

Frank Welty and Raymond D. Welty, Youngstown, Ohio, assignors to Carbonic Dispenser, Inc., Canfield, Ohio, a corporation of Ohio

Application February 8, 1951, Serial No. 209,941

9 Claims. (Cl. 137—657)

1

This invention relates to faucets and valves and more particularly to means for accurately and effectively controlling the flow of carbonated liquids under high pressure.

An object of this invention is the provision of a novel device for dispensing beer, soft drinks, carbonated water, and the like.

A more specific object of this invention lies in the provision of a faucet of this type wherein a novel arrangement of parts is utilized to provide a compact unit of utmost simplicity, yet which is operative to accurately control the flow of carbonated liquids with a minimum loss of carbonation.

Another object of this invention is the provision of a faucet of this type wherein the various components are of utmost simplicity in design and may be manufactured without the use of specialized machinery.

Yet another object of the invention is the provision of a faucet of the character described which may be easily and quickly assembled and disassembled, for such cleaning and repairs as may be deemed necessary, by a person not particularly skilled in mechanics, without the aid of tools.

A further object of this invention is the provision of a faucet of this type embodying a novel principle of operation whereby opening and closing of the valve is greatly facilitated.

A still further object of the invention is the provision of a faucet of this type wherein several embodiments of the apparatus, incorporating different principles of operation may be realized through a mere substitution of interchangeable parts.

Other objects and advantages of the invention will become apparent upon full consideration of the following detailed specification and accompanying drawing wherein are shown certain preferred embodiments of our invention.

In the drawing:

Figure 1 is an axial section of a dispensing valve constructed according to the principles of our invention;

Figure 2 is an axial section of a second embodiment of our invention wherein remote operation is utilized;

Figure 3 is a third embodiment of our invention wherein a self-closing feature is utilized; and

Figure 4 is a section view taken along line IV—IV of Figure 3.

As will be noted throughout the following disclosure the dispensing faucet of our invention has been constructed in such manner as to effect

1 a high degree of versatility. As will be understood, there are many types of dispensing faucets of this character which are in demand to suit the varied requirements of taverns and soda fountains. For example, an establishment which realizes an essentially constant but not excessively high demand upon its fountain facilities may desire the type of faucet shown in Figure 3 wherein in uneven distribution of internal pressure is utilized to cause the valve to automatically close when released by the operator. On the other hand, many establishments cater to a predominantly "rush hour" trade, in which case a large demand must be served within the shortest possible time. For this class of establishment the type of faucet shown in Figure 1 may be best suited. In this instance the construction of the faucet is such that the valve will remain in the position set by the operator thus permitting the attendant to use both hands for rapid handling of glasses. Yet another form of dispensing faucet in common use today is the remotely operated type shown in Figure 2. This type of faucet is generally utilized in automatic coin-operated vending machines such as may be found in theater lobbies, factories, etc.

20 As will become apparent, the faucet of our invention is of such utilitarian design that the various components which comprise the three embodiments shown in the drawing, if not identical in each, are interchangeable with corresponding parts. Thus the manufacturing cost of our faucets is maintained at a minimum since our construction renders the various types of faucets 25 available with a minimum variance in construction.

30 In reference now to Figure 1, the reference numeral 10 denotes a casing or body member which is generally cylindrical in shape and which is threaded at both ends at 11 and 12. An aperture 13 is provided in the side wall of the casing 10 to receive an inlet fitting 14 which is rigidly secured to the casing in any suitable manner and which generally has provisions, not shown, 35 at its outer end portion by which it may be secured to a dispensing cooler, also not shown. The inlet fitting 14 is provided with an axial bore 15 which connects the casing 10 with a pressurized source of beer, or other carbonated liquid, not shown. Secured to the lower end of the casing 10 by means of threads 12 is a discharge nozzle 16 which has an outlet aperture 17 disposed axially therein. A resilient gasket 18 is positioned 40 between the casing 10 and nozzle 16 to effect a fluid tight seal therebetween. The bore 17 in the

nozzle 16 is enlarged slightly at 18' to snugly receive a discharge tube 19 which extends upwardly into the casing 10.

It is, of course, understood that the fluid which enters the inlet bore 15 is under a considerable pressure, as is necessary to properly retain sufficient carbonation. In order to prevent spitting or spraying of the liquid from the valve, it is necessary to reduce the liquid pressure to substantially that of the atmosphere, to thus allow a gravity flow of the liquid from the faucet. To accomplish this reduction in pressure we provide a flow restricting member 20 which is in the form of an inverted cup and which is adapted to fit slidably into said casing. The upper portion of the cup shaped restricting member 20 is provided with a flange 21 which is adapted to rest upon a shoulder 22 provided therefor in the casing 10 and thus serves to retain the member 20 in the proper axial position. An annular recess 23, provided in the upper portion of the cup member 20 at a position substantially adjacent the inlet bore 15, permits fluid entering through the bore 15 to circulate freely around the cup 20. In accordance with principles disclosed in our related U. S. Patent No. 2,331,527, we provide a slight clearance between the inner wall of the casing 10 and the periphery of the cup member 20 through which the fluid must pass to be discharged. This clearance is in the order of 0.010 to 0.012 inch and is operative to reduce the fluid pressure substantially to atmospheric as is required for effective operation. A plurality of circumferentially arranged spacers 24 are positioned about the periphery of the cup member 20 at its lower end and serve to retain the said member 20 in concentric relation with the casing 10. To secure the cup member 20 in position we provide a cap member 25 which is adapted to fit slidably into the casing 10 and to abut the upper end portion of the cup member 20 as shown. A key 36 is retained in the cap 25 and slidably engages a keyway 37 provided therefor in the casing 10 to insure proper alignment of the parts as may be desired. A threaded collar nut 26 is adapted to engage the threads 11 provided at the upper end of the casing and to bear against the upper portion of a flange 21 which extends from the cap 25. As may be observed, tightening of the collar nut 26 exerts a force through the flange 21 to the cap member 20 to retain it firmly in contact with the shoulder 22. To prevent the leakage of fluid upward around the cup member 20 we have provided an O-ring gasket 38 which is retained between the cap 25 and the cup member 20 and is operative to effect a fluid seal at the junction of the said parts 20 and 25 with the casing 10.

The valving means of our faucet comprises an actuating shaft 28 which is adapted to retain a resilient washer 29 at its lower end, and which is slidably retained in both the cap member 25 and cup member 20. An O-ring gasket 39 is retained between the members 20 and 25 and in contact with the shaft 28 to prevent leakage of the pressurized fluid. As shown, the washer 29 is apertured centrally and is retained in contact with the shaft 28 by means of a flanged stud 30 which engages mating threads in the shaft 28. A tapering plug 31 extends downwardly from the stud 30 and into the discharge tube 19, for reasons to be hereafter disclosed. As will be noted, movement of the shaft 28 is operative to move the washer 29 into and out of sealing contact with the end of the discharge tube 19. To accom-

plish this movement we provide an operating arm 32 which is pivotally mounted in a recessed portion of the cap member 25 by a pin 33. The pin 33 is firmly retained at its extremities by the cap 25. Extending inwardly from the lower end of the operating arm 32 is a bifurcated lifter 34 which straddles the shaft 28 near its upper end at 35, at which point the shaft has been sufficiently recessed to insure positive response to movement of the lifter 34 in either direction. It may be observed that no retaining devices are necessary to retain the shaft 28 at a set position; the slight friction between the shaft and the gasket 39 being ample to accomplish this.

Further, closing of the valve causes the full fluid pressure to be exerted upon the upper side of the washer 29 to thus firmly retain it in the closed position to avoid dripping.

In the operation of our faucet the operating arm 32 is pulled downward to lift the washer 29 from its seat 19 and thus permit the flow of fluid. The fluid, entering through the bore 15, flows through the restricted passage between the casing 10 and the cup 20 where it undergoes a substantial loss of pressure. After passing through the above mentioned clearance it is emitted at the lower end of the cup 20 and discharged into a surge chamber space provided between the tube 19 and the cup 20. This space is normally filled with liquid which is under no appreciable pressure when the valve 29 is open. Therefore any discharge velocity in the entering liquid is quietly killed. This is important since carbonated beverages readily lose this carbonation if agitated at low pressures and the least turbulence greatly increases the discharge of the dissolved gases.

As is well known in the art, there is a natural tendency for liquids discharged from a tube, as in the instant case, to form a low pressure air pocket at the point of discharge. This further increases the carbonation loss and is thus undesirable. To avoid the formation of this air pocket we have provided the tapering plug 31 which displaces the air at the point of formation and thus is operative to substantially preclude such formation.

As explained, closing of the valve by moving arm 32 to an upright position causes the full pressure of the liquid to be applied to the upper portion of the valve to thus exert a strong sealing force which is proportional to the pressure of the fluid retained. However, upon the valve being opened, such force is relieved and the valve is biased to open position by such pressure as exists in the outflowing liquid. This, together with the friction of the stem 28 and the O-ring 39, is sufficient to hold the valve in open position.

The embodiment of our invention shown in Figure 2 is of essentially the same structure as that shown in Figure 1 with alterations as will be disclosed below. Components which are identical in both embodiments will be denoted by corresponding reference numerals and will not be redescribed except as is required to support the additional disclosure.

Shown in Figure 2 is an embodiment of our invention which is particularly adapted for use in automatic vending machines and the like where remote control is desired. In this embodiment the cap 25' is terminated at the flange 27' and functions merely to retain the cup 20 in position and to retain the O-rings 38 and 39. The actuating shaft 28' is threaded at its upper end and retains at that point a piston 40. Re-

placing the collar nut of Figure 1 we have provided an internally flanged cylinder 41 which has an integral nut 26' at its lower end, and as such functions to retain the cap 25 as well as to enclose the piston 40, as shown. A suitable fitting 42 is secured to a cylinder 41 at a point beneath the piston 40 and is connected to a source of air or gas pressure, not shown. A solenoid actuated valve 43, which is interposed in the supply conduit 44, operates in response to the energization of solenoid 45 to apply pressure to the lower side of the piston 40 to thus open the valve. It is presently common practice to utilize a suitable timing device, not shown, in the energizing circuit so that the valve 43 will remain open for a predetermined length of time to allow a likewise predetermined volume of liquid to be dispensed.

In order to return the valve to a closed position after deenergization of the solenoid 45 we provide a compressible coil spring 46 which is retained in engagement with the upper side of the piston 40 by means of a cover piece 47. The cover piece 47 is retained in threaded engagement with upper end of the cylinder 41 as shown.

The embodiment of our invention shown in Figure 3 employs a principle of operation which features automatic closing of the valve after release of the operating arm 32. In this embodiment the shaft 28" and the cup 20' are integral and move together with the washer 29 to open or close the valve in response to movement of the arm 32. As will be understood, the large drop in fluid pressure through the clearance provided between the casing 10 and cup 20' causes a substantial differential in force applied by the liquid to the cup. The force applied to the upper side, being the larger, causes the valve to close immediately upon release of the arm 32. In order to effect a seal between the casing 10 and the cap 25 we provide an apertured disc 21' which corresponds to the flange 21 of the cup 20 utilized in the embodiment shown in Figure 1.

The embodiments of our dispensing faucet shown in Figures 1 and 2 are so constructed that the flow restricting cup 20 is permanently positioned while the valving element alone is operative to move to effect control of the liquid flow, the construction being such that liquid flowing through the faucet exerts substantially no force upon the valving member, and thus exhibits no tendency to open or close the valve. Further, the construction of our faucet is such that it may be easily and quickly assembled and disassembled without the aid of tools. Thus the fountain attendant, though unskilled in the art, may easily perform such repairs and cleaning operations as become necessary from time to time. This is of considerable importance since the syrup base used in most carbonated soft drinks is apt to congeal within the faucet and it may well be understood that over a relatively short period of time a valve may become extremely sticky and thus fail to function properly. By providing a construction which so facilitates cleaning of the faucet that little time and no tools are required we have rendered the task one of such insignificance that it is much less likely to be neglected.

Our general construction is also of extreme versatility as may be noted from the drawing alone. With but few minor alterations in parts the faucet of Figure 1 may be transformed into the prior type, self-closing embodiment shown in Figure 3. Further, either of these types may

be rendered automatic in operation by substitution of the piston or cylinder arrangement shown in Figure 2 for the operating arm of Figures 1 and 3. Thus it should be apparent that costs of manufacturing may be greatly reduced since many major parts are common to the three embodiments. It may be noted also that with but few minor exceptions all machinery operations required in the manufacture of our faucets may be accomplished with a lathe and drill press. The manufacture of our faucets, then, may be accomplished by relatively unskilled operators, and does not require the services of skilled machinists.

It should be understood, however, that the embodiments of our invention herein shown and specifically described are intended to be illustrative only since obvious alterations may be made therein without departing from the spirit or scope of the invention. Reference should therefore be had to the appended claims in determining the true scope of the invention.

We claim:

1. In a liquid dispensing faucet an upstanding cylindrical casing having an enlarged bore extending vertically therethrough and an inlet aperture in its side wall; an outlet nozzle carried by said casing at its lower end; a discharge tube retained in said nozzle and extending upwardly into said casing; a cup member adapted to be slidably assembled within said casing and positioned over said discharge tube, the arrangement being such a relatively restricted fluid passage, communicating with said inlet aperture, is formed between said casing and said cup and a relatively unrestricted surge chamber, communicating with said restricted passage and said discharge tube, is formed between said cup and said tube; a cap member adapted to fit slidably into said casing and having an outwardly extending flange adapted to overlie the upper end portion of said casing, said cap member having a centrally positioned axial bore; a nut adapted to screw-threadedly engage the upper end of said casing and to engage the flange of said cap member to thereby retain said cap member in said casing; a shaft slidably retained in the said bore in said cap member and extending downwardly toward said tube; a resilient washer secured to the lower end of said shaft and adapted to sealingly engage the upper end of said discharge tube; a tapered plug carried by the lower end of said shaft and extending downwardly into said discharge tube; and means to slide said shaft upwardly and downwardly to thereby move said washer into and out of sealing engagement with said discharge tube.

2. Apparatus according to claim 1 further characterized by said shaft moving means comprising an operating arm pivotally mounted in said cap member and a lifter rigidly extending from said operating arm and engaging said shaft, said lifter being adapted to move said shaft in response to movement of said operating arm.

3. Apparatus according to claim 1 further characterized by said shaft moving means comprising a cylinder extending integrally upward from said nut; a piston slidably in said cylinder, said piston being secured to said shaft; conduit means connecting said cylinder with a source of fluid pressure, valve means interposed in said conduit to control the application of fluid pressure to said cylinder, the arrangement being such that application of said fluid pressure to said cylinder will cause said piston to move in one di-

rection; and biasing means operative to move said piston in the other direction upon the release of fluid pressure from said cylinder.

4. In a liquid dispensing faucet an upstanding cylindrical casing having an enlarged bore extending vertically therethrough and an inlet aperture in its side wall, an outlet nozzle carried by the lower end of said casing, a discharge tube retained in said nozzle and extending upwardly into said casing in concentric relation thereto, a cup member adapted to be slidably assembled into said casing and to be positioned over said tube; the arrangement being such that a relatively restricted fluid passage, communicating with said inlet aperture, is formed between said casing and said cup, and a relatively unrestricted surge chamber, communicating with said restricted passage and said discharge tube, is formed between said cup and said tube, said cup member having a flange at its upper end adapted to engage a shoulder provided therefor in said casing to thereby insure positive axial positioning of said cup member; a cap member adapted to fit slidably into said casing and to abut the upper end portion of said cup member, said cap having a flange adapted to overlie the upper end of said casing; a nut adapted to screw-threadedly engage the upper end of said casing and to engage said last mentioned flange to thereby firmly retain said cap member and said cup member in position; a shaft slidably retained in said cap member and said cup member; a resilient washer carried by the lower end of said shaft and adapted to sealingly engage the upper end of said discharge tube; a tapered plug carried by the lower end of said shaft and extending downwardly therefrom into said discharge tube; and means associated with the upper end of said shaft operative to move said shaft axially and hence move said washer into and out of fluid sealing engagement with said discharge tube.

5. In a liquid dispensing faucet an upstanding cylindrical casing having an enlarged bore extending vertically therethrough and an inlet aperture in its side wall; an outlet nozzle carried by the lower end of said casing; a discharge tube retained by said nozzle and extending upwardly into said casing in concentric relation thereto; a cup member adapted to be slidably retained within said casing and over said discharge tube, the arrangement being such that a relatively restricted passage, communicating with said inlet aperture, is formed between said casing and said cup, and a relatively unrestricted surge chamber, communicating with said restricted passage and said discharge tube, is formed between said cup and said tube; a washer carried by the upper or closed end of said cup and adapted to sealingly engage the end of said discharge tube; a tapered plug carried by the end of said shaft and extending downwardly into said tube; a shaft extending integrally upward from said cup; an apertured disc slidably received within said casing and over said shaft and adapted to engage a shoulder provided therefor in said casing; a cap member adapted to be slidably received within said casing and over said shaft, and adapted to abut said disc, said cap member having a flange adapted to overlie the upper end portion of said casing; a nut adapted to screw-threadedly engage the upper portion of said casing and to engage said flange to thereby firmly retain said cap and said disc in position; and means positioned in said cap and associated with the upper end of said shaft to effect vertical

movement of said shaft and said cup whereby said washer is moved into and out of fluid sealing engagement with said discharge tube.

6. In a liquid dispensing faucet an upstanding cylindrical casing having an enlarged bore extending vertically therethrough and an inlet aperture in its side wall; an outlet nozzle carried by the lower end of said casing; a discharge tube retained by said outlet nozzle and extending upwardly into said casing; a cup member adapted to be slidably assembled into said casing and over said tube, the arrangement being such that a relatively restricted passage, communicating with said inlet aperture, is formed between said casing and said cup, and a relatively unrestricted surge chamber, communicating with said restricted passage and said discharge tube, is formed between said cup and said tube; a cap member slidably received in said casing and adapted to abut the upper end of said cup member; detachable means to retain said cap member in aforesaid relation; a shaft slidably received in said cap member and said cup member and extending downwardly toward said tube; a resilient washer carried by the end of said shaft and adapted to sealingly engage said tube; means associated with the upper end of said shaft to impart vertical motion thereto whereby said washer may be moved into and out of fluid sealing contact with said tube.

7. In a liquid dispensing faucet a cylindrical casing having an enlarged bore extending vertically therethrough and an inlet aperture; an outlet nozzle carried by the lower end of said casing; a discharge tube retained in said nozzle and extending upwardly into said casing; a cup member adapted to be slidably assembled into said casing and adapted to fit over said tube, the arrangement being such that a relatively restricted passage, communicating with said inlet aperture, is formed between said casing and said cup, and a relatively unrestricted surge chamber, communicating with said restricted passage and said discharge tube, is formed between said cup and said tube; means to retain said cup in said thus assembled position; a shaft slidably received in said cup member and extending downwardly toward the said tube; a resilient washer carried by said shaft and adapted to sealingly engage said tube; and means associated with said shaft to impart vertical motion thereto whereby said washer may be moved into and out of fluid sealing contact with said tube.

8. In a faucet for dispensing carbonated beverages and the like the combination of a casing having a vertically extending bore therein and an inlet aperture in the side wall thereof communicating with said bore, an inverted cuplike member received and normally fixed in said bore and having a depending cylindrical wall positioned closely adjacent but spaced from the inner surface of the bore below said aperture to provide a relatively restricted passage for liquid to be dispensed, said cup being circumferentially recessed to provide for the circumferential distribution of liquid received through said inlet aperture to said restricted passage, means positioned above said inlet aperture to seal the upper end of said cup-like member in said bore against the leakage of fluid, and means to discharge liquid from the space within said cup-like member, said last mentioned means including a valve to control the discharge of liquid from said space, said valve being positioned within said space and

being movable independently of said cup-like member.

9. In a faucet for dispensing carbonated beverages and the like the combination of a casing having a vertically extending bore therein and an inlet aperture in the side wall thereof communicating with said bore, an inverted cuplike member received and normally fixed in said bore and having a depending cylindrical wall positioned closely adjacent but spaced from the inner surface of the bore below said aperture to provide a relatively restricted passage for liquid to be dispensed, said cup being circumferentially recessed to provide for the circumferential distribution of liquid received through said inlet aperture to said restricted passage, means positioned above said inlet aperture to seal the upper end of

said cuplike member in said bore against the leakage of fluid, a discharge tube extending upwardly within said cylindrical wall to form therewith a liquid trap, said tube having an open upper end, a valve member for opening and closing said open upper end, and a valve stem carrying said valve member and slidably received in a bore formed in the upper wall of said cuplike member.
